UNITED STATES PATENT OFFICE.

ALFRED HALL, OF BOSTON, MASSACHUSETTS.

DESIGN FOR A GAME-BOARD.

49,304.

Specification for Design.

Patented July 4, 1916.

Application filed April 6, 1916. Serial No. 89,500. Term of patent 14 years.

To all whom it may concern:

Be it known that I, **ALFRED HALL**, a citizen of the United States, residing at Boston, in the county of Suffolk and Commonwealth of Massachusetts, have invented a new, original, and ornamental Design for Game-Boards, of which the following is a specification, reference being had to the ac-

companying drawing, forming a part thereof.

The figure is a perspective view of a game board, showing my new design.

I claim:

The ornamental design for a game board, as shown.

ALFRED HALL.
